UNITED STATES PATENT OFFICE.

WILLIAM M. QUICK, OF HUNTSVILLE, ALABAMA, ASSIGNOR OF NINE-FORTIETHS TO H. M. STRONG AND L. G. EVERETT, PARTNERS UNDER NAME OF EVERETT & STRONG, NINE ONE-HUNDREDTHS TO R. C. RAND, NINE ONE-HUNDREDTHS TO W. R. ROUSSEAU, NINE TWO-HUNDREDTHS TO J. A. PERRY, ONE-TENTH TO GEORGE P. COOPER, ALL OF HUNTSVILLE, ALABAMA.

INTERNAL-COMBUSTION ENGINE.

Application filed May 29, 1920. Serial No. 385,163.

To all whom it may concern:

Be it known that I, WILLIAM M. QUICK, citizen of the United States, residing at Huntsville, in the county of Madison and State of Alabama, have invented certain new and useful Improvements in Internal-Combustion Engines; and I do hereby declare the following to be a full, clear, and exact description of the invention, such as 10 will enable others skilled in the art to which it appertains to make and use the same.

This invention relates to improvements particularly in internal combustion engines.

The invention has for its object, among 15 other things, principally to utilize or re-use a part of the exhaust gases which are characterized for the retention of a certain amount of combustible matter, as the same is taken from the exhaust-manifold and delivered to the carbureter for the ultimate reduction in the amount of gasoline used. As advantages of this method of carrying out my invention it is possible to greatly increase lubricating efficiency, eliminate 25 carbon-deposits, sticky valve-guides, frozen piston-rings, scored cylinders, dilution of oil in the crank-case, and prevent gases passing the piston. While providing for the reduction in the consumption of gasoline, I 30 obtain the same amount of power-generating efficiency. Also it is observed that by my method of introducing hot exhaust gases from the exhaust manifold to the carbureter a more perfect combustible mixture is obtained than has heretofore been the case, this resulting from the breaking up and causing complete vaporization of the wet 35 particles of the gasoline in the carbureter.

The invention consists therefore in certain 40 features of construction, substantially as hereinafter more fully disclosed and particularly pointed out in the appended claim.

The accompanying drawings illustrate the 45 preferred embodiment of my invention or one example thereof, wherein it will be understood that various changes and modifications as relate to the detailed construction and arrangement of parts, may be made 50 without departing from the spirit of my in-

vention as covered by the claims, and in which drawings—

Fig. 1 is side elevation of an internal combustion engine, showing my invention as applied thereto in practical use.

Fig. 2 is a fragmental detailed sectional view showing more particularly the air intake for the carbureter and the butterfly valves with their operating means.

As characteristic features of my invention, I employ in connection with exhaust manifold 1 of an internal combustion engine and the intake manifold 2 thereof, together with a carbureter 3, a pipe connection 4, leading from said exhaust manifold to 60 said carbureter, said pipe being let into the open end of the latter, and being much less in diameter than the intake of said carbureter. Pipe 4 is adapted to take a portion of the exhaust gases from the exhaust-manifold and deliver the same into the carbureter, the amount of said gases being restricted within certain limits in order that only a limited or prescribed amount of such 65 gases may be introduced into the carbureter, 70 so that the gasoline vapor from the carbureter may be delivered through a pipe 5, in a hot condition, into the intake-manifold 2, said pipe effecting connection between the carbureter and intake-manifold.

It will be observed that, by this means the gasoline vapor will be freed of moisture, also carbon deposits, while other objections such as sticky valve-guides, frozen piston-rings, scored cylinders, dilution of oil in 85 the crank-case, will be eliminated and gases be prevented from passing the piston; also by this arrangement provision will be made for the reduction in the consumption of the gasoline, yet the same will retain its power- 90 generating efficiency.

Also it is observed that by means of this method of introducing hot exhaust gases from the exhaust-manifold to the carbureter, a more perfect combustible mixture is obtained than has heretofore been the case, this resulting from the breaking up and causing more perfect vaporization of the wet or moist particles of the gasoline in the carbureter. Also by 95 means of this arrangement, combustible 100

matter in the exhaust-manifold and exhaust gases will be utilized, or re-used, in vaporizing the gasoline vapors passing from the carbureter, whereby the gasoline will be 5 freed of impurities or unutilizable particles and the quantity of gasoline thus used be economized or lessened.

Within the intake pipe of the carbureter is arranged a butterfly valve 6, and similarly 10 arranged in the pipe 4 is a like valve 7, said valves being co-jointly operable by means of levers 8, and 9 and the rod 10, for controlling the supply of air and hot gases to the carbureter, the carbureter being supplied with gasoline by pipe 11. In the pipe 15 5 at the intake manifold end, is preferably arranged what may be called a "screen" 12 to prevent the back-firing of the gas.

From the foregoing description of the 20 construction and operation of my invention, it is believed that the same will be readily appreciated or understood by those familiar with this class of device.

Having thus described my invention, I 25 claim as my invention and desire to secure by Letters Patent:

In an internal combustion engine, the combination with an exhaust manifold and an air-intake manifold of a carburetor provided with an air intake and means for delivering part of the hot gases from said exhaust manifold into said air intake, said means comprising a tubular member having one end opening into said exhaust manifold, the other end being of smaller diameter than 30 said air-intake and inserted freely therein, the walls of said tubular member being arranged in parallelism and in concentric relation with the walls of the air-intake, whereby the air entering said air-intake is 35 provided with a core of hot exhaust gases, a valve within said tubular member and adjacent the open end thereof, a valve within the air-intake adjacent the open end thereof and being arranged in proximity to the end of the tubular member, and means for operating both of said valves 40 conjointly to regulate the mixture of hot exhaust gas and air entering said air-intake.

In testimony whereof, I affix my signature. 45

WILLIAM M. QUICK. 50
